EJECTOR LOCK AND CONDITIONING
MEANS FOR DICTATION MACHINESHenry P. Roberts, Brooklyn, N. Y., assignor to
Dictaphone Corporation, New York, N. Y., a
corporation of New YorkApplication May 11, 1929, Serial No. 362,364
Renewed July 27, 1932

13 Claims. (Cl. 274—17)

This invention relates to dictation machines and more particularly to ejector locks therefor.

An object of the invention is to provide a simple, effective and dependable device of the nature described. A further object is to provide in a machine of the above character wherein the record cylinder is removed from the supporting mandrel by manipulation of a record ejector, simple and practical means for preventing possible injury to the stylus or related parts by reason of the operation of said ejector. Another object is to provide practical means of the character described adapted to prevent manipulation of the record ejector while the stylus is in operative position relative to the record cylinder. Other objects will be in part obvious and in part pointed out hereinafter.

This invention accordingly consists in the features of construction, combinations of elements and arrangements of parts which will be pointed out in the following description, and the scope of the application of which will be indicated in the appended claims.

In the accompanying drawings in which is shown one of the various possible embodiments of my invention:

Figure 1 is a front plan view of a dictating machine, of the transcribing type, showing the present invention as applied thereto.

Figure 2 is a top plan view of a portion of the dictation machine shown in Figure 1, partly in section and with parts removed to more clearly show certain features of the present embodiment of my invention.

Figure 3 is an end elevation of the dictation machine shown in Figure 1 and shows the reproducing stylus in operative position, with the ejector latch in ejector locking position.

Figure 4 is a cross section taken on line 4—4 of Figure 1, showing the reproducing stylus and related parts in their inoperative position with the ejector lock moved to non-locking position by the guide arm of the carriage.

Before referring to the drawings for a detailed description of the structural features of the illustrated embodiment of my invention, it may here be explained that dictation machines of the nature of that herein described are usually provided with means for ejecting the record cylinder from its supporting mandrel whenever the operator so desires, irrespective of the longitudinal position of the sound box carriage relative to the record cylinder, so that the ejector mechanism may be actuated inadvertently while the stylus is in operative engagement with the cylinder. Should this hap-

pen when the carriage occupies a position intermediate the ends of the record cylinder, as for example, in the position shown in Figure 1, the stylus will drop down after the record has been removed, to the position it occupies in Figure 3, a position within the boundary of the cylinder's outer circumference. Should the operator fail to raise the stylus from this position before attempting to place a new record upon the mandrel, it is extremely likely that the end of the record will collide with the stylus with considerable impact, in which event, not only will the delicately balanced parts of the sound box be strained or thrown out of adjustment, but there is even the possibility that the stylus itself may become chipped or broken. Any distortion of the delicately balanced parts of the sound box or stylus supporting means adversely affects recording or reproducing to a marked extent, and if the stylus should be chipped or broken, its replacement or repair is a factor of much consequence because it cannot be easily accomplished, and the replacement cost is necessarily great because the stylus is usually made of either a diamond or a sapphire. The present invention overcomes these possibilities in a very simple and novel manner.

Referring to the drawings it will be seen to comprise a main frame 10 and an integral housing 11 which serves as a bearing support for the mandrel shaft 12. The mandrel shaft is provided with a record support or mandrel 13 at one end, which is rotated by a driving pulley 14 at its other end, under the influence of an electric motor or other prime mover, not shown.

The main frame 10 is also provided with an integral left hand standard 15 and right hand standards 16 and 17. The sound box carriage 18 is supported for longitudinal movement relative to the record support 13 upon a front or main carriage rod 19 supported between the left hand standard 15 and right hand standard 16, and a rear guide rod 20, supported between the housing 11 and the right hand standard 17.

The carriage is provided with a control which makes it possible to condition the same so as to allow manual movement of the carriage freely to and fro upon the carriage guide rods 19 and 20, or to condition the carriage to effect a mechanical advance of the same in predetermined ratio with the rotatable record support 13 under the influence of rotatable feed screw 21, driven by the driving pulley 14 and the mandrel shaft 12 through any suitable train of gears (not shown) within the housing. This mechanical advance of the sound box carriage is effected by

engagement of a feed nut 22 with the rotatable feed screw.

The sound box 23, shown in the present drawings, is of the acoustic type and comprises a 5 producing stylus 24 pivotally supported for up and down movement about the pin 25, the other end of the stylus supporting lever 26 being connected in a well known manner through the wire 27 to a diaphragm (not shown) positioned within 10 in the sound box 23. The pin 25 is mounted within a projecting part of a stylus carrier or weight 28, pivotally mounted at 28a to give to the stylus a limited range of up and down movement relative to the mandrel 13, to provide for 15 its proper engagement with record cylinders of various diameters, as for example, the cylinder 29, and to accommodate itself to any slight eccentricity or runout of a record cylinder.

The stylus carrier 28 and related parts are 20 conditioned by a control lever 30, which is pivotally mounted upon the carriage guide rod 19 within an opening 31 formed in a forward portion of the carriage. This control lever is provided with a lobe 32 adapted to swing the carrier 28 about 25 the pin 28a by engaging an extension of the carrier and thereby forcing said carrier to the position shown in Figure 4. At the same time, a lobe 34 formed upon the control lever engages an upturned portion 35 of the feed nut 22 and 30 swings the feed nut about its pivot 22a out of operative engagement with the feed screw. By moving the control lever to the down position shown in Figure 3 the lobe 34 is withdrawn from engagement with 35 and allows the feed nut to 35 reengage the feed screw under the retractive influence of the spring 22b, while at the same time the lobe 32 is withdrawn from contact with 33 and permits the stylus carrier 28 to return to its operative position under the retractive influence of 40 spring 28b.

In the usual operation of the machine, a record cylinder 29 is placed upon the mandrel 13 when the carriage 18 is in its innermost or starting position of travel, that is, near the head end 45 or housing end of the machine, and when the sound box and feed nut are conditioned by the control lever as shown in Figure 4. After the record is placed fully upon the mandrel, as shown in Figure 1, the operator moves the control lever downwardly to permit of the stylus 50 engaging the record cylinder and to allow movement of the feed nut into engagement with the rotatable feed screw, as hereinbefore described, thus rendering the machine fully operative for 55 the purpose of reproducing dictation.

Further, in the normal operation of the machine, dictation is reproduced by the progressive travel of the carriage and sound box longitudinally of the record cylinder and by the contact 60 of the sound box stylus with a spiral sound groove previously traced upon the record cylinder, in a well known manner, until the sound box carriage approaches the end of the dictation area or the end of the cylinder, or to a position like that 65 shown in Figure 1. When such a position is reached, should the operator desire to change the record cylinder, means is provided for ejecting the record cylinder from the mandrel.

In the present drawings, the type of record 70 ejector shown is substantially the same as that disclosed in the Lucarelle Patent, No. 1,687,375, but it should be understood that the invention is equally applicable with other types of record ejectors. The record ejector shown comprises a plunger 36 supported in a bearing 37 formed

integrally with the housing 11, in a position to move longitudinally of the machine. The operating end of the plunger has a head 38, so shaped as to pass by the flange 39 at the inner end of the mandrel 13 and is adapted to engage the end of the record when the plunger is reciprocated. The other end of the plunger is fastened to the upstanding arm 40 forming part of a longitudinally disposed link 41. This link extends below the base of the frame 10 and terminates at a point adjacent the outer end of the mandrel. Here the link is connected to a lever 42 by means of a shoulder stud 43. The lever 42 is fulcrumed upon a stud 44 at the rear of the machine, and at its forward end is provided with an upwardly extending portion 45 forming a finger piece by means of which the ejector may be operated.

The finger piece extends through a slotted plate 46 covering a suitable opening 47 left in the base of the frame 10. The ends of the slot in 95 the plate 46 serve as stops for limiting the movement of the lever 42.

The parts are held in their normal position by means of a spring 48 having one end connected to the lever and the other end connected to a 100 stud 49 which is on the under side of the main frame, as shown in Figure 2. The tendency is for the spring to pull the lever 42 to the left, as seen in Figure 2, and when the lever moves to the left the link 41 and plunger 36 must also 105 move to the left where the spring yieldingly maintains the entire device in inoperative position. If desired, the link 41 may be guided in its movement by a shoulder screw 50 passing through a slot 51 in the link. This will hold the 110 lever connected with the link against undesirable downward movement.

The finger piece 45 is arranged so as to project above the base 10 in close proximity to the end of the mandrel 13. This enables the removal of 115 the record by the operator's thumb engaging the finger piece 45 while the index and middle fingers are in engagement with the end of the mandrel, which is used as a purchase for operating the record ejector.

In its present preferred embodiment, the invention provides means to lock the record ejector against operation as soon as the sound box carriage moves from the initial or starting position of travel to any station longitudinally of the record, making it necessary for the operator to raise the control lever 30 to move the stylus and feed nut to inoperative position and return the carriage to initial or starting position of travel before he can manipulate the record ejector. 130 This means comprises a simple latch 52 pivotally mounted on a stud 53 on housing 11 at the head end of the machine. This latch is adapted to swing by gravity into the path of the ejector plunger shoe 38 under the influence of a counter- 135 weight portion 54, as shown in Figures 1, 2 and 3. While the latch is in this position the ejector parts are locked against operation. However, when the carriage is in the starting position of travel the latch 52 is pressed downwardly out of 140 the path of the record ejector plunger shoe by a portion of the guide arm 55 of the sound box carriage engaging a tapered arm 56 which extends outwardly from the pivotally mounted latch 52, as shown in Figure 4. With this arrangement of 145 parts, a very simple and effective safety device is provided. Its operation is as follows:

A record cylinder is placed upon the mandrel when the sound box carriage is in the starting position of travel or at the head end of the ma- 150

chine, as shown in Figure 4. The operator then moves the control lever into the down position, as shown in Figure 3, when the feed nut engages the feed screw and the stylus engages the record 5 sound grooves on the periphery of the record cylinder. The dictated matter will be reproduced while the carriage is fed longitudinally along the record by the rotating feed screw, during which time the mandrel and the recording cylinder rotates. When the sound box carriage has moved a short distance, its guide arm 55 will move out of 10 engagement with the latch arm 56 permitting the latch to swing upwardly into locking position by reason of the gravitational action of the 15 counterweight. This relation of parts is shown in Figure 1 wherein the guide arm of the carriage is indicated by a dot and dash outline in a position just clear of the latch arm, with the latch in ejector locking position. At any position 20 thereafter in the longitudinal movement of the carriage it is first necessary for the operator to move the control lever and related parts into neutral or inoperative position, and then return the carriage to starting position of travel before 25 he can operate the record ejector. This insures that the stylus and related parts will not be in the operative position, as shown in Figure 3, and in the path of a record cylinder should one now be placed upon the mandrel, while the carriage 30 occupies other than its starting position.

From the foregoing it will be seen that this invention is one well adapted to attain the aims and objects hereinbefore set forth in a simple, practical and dependable manner.

As various embodiments might be made of this invention, and as various changes might be made in the construction herein described, all without departing from the scope of the invention, it is to be understood that all matter herein set forth 35 or shown in the accompanying drawings is to be interpreted as illustrative and not in a limiting sense.

What I claim as new and seek to protect by Letters Patent is:

1. In a dictation machine, in combination, a frame, a record support mounted on the frame, a record ejector movably mounted for freeing a record from said support, a carriage movable on said frame along said record support from an 45 initial position, a stylus on said carriage adapted to track the record, means for normally locking said ejector to prevent its engagement with the record, and means co-acting with said locking means to release said ejector when said carriage 50 is moved to its initial position.

2. In a dictation machine, in combination, a frame, a record support mounted on the frame, a record ejector movably mounted for freeing a record from said support, a carriage movable on 55 said frame along said record support from an initial position, a stylus on said carriage adapted to track the record, a latch normally held in position to obstruct the path of movement of said ejector, and means for forcing said latch from said path when the carriage is moved to its initial position.

3. In a dictation machine, in combination, a frame, a record support mounted on the frame, a record ejector movably mounted for freeing a record from said support, a carriage movable on 60 said frame along said record support from an initial position, a stylus on said carriage adapted to track the record, a latch normally held by gravity in a position to block movement of said 65 ejector and having a contact surface adapted to

be engaged by a portion of said carriage to render said latch inoperative.

4. In a dictation machine, in combination, a record support, a movably mounted record ejector, a carriage movable from a starting position relatively to said record support, a stylus mounted on said carriage and movable into and out of operative relation to said record support, means positioned to be engaged by said ejector for locking said record ejector against operative movement, means coacting with said locking means to release said ejector when said carriage is moved to starting position, and means adapted to prevent such movement of said carriage when said stylus is in operative relation to said record support. 80

5. In a dictation machine, in combination, a record support, a movably mounted record ejector, a carriage movable from a starting position relatively to said record support, a stylus on said carriage adapted to track the record, means positioned to be engaged by said ejector for locking said record ejector against operative movement, means coacting with said locking means to release said ejector when said carriage is moved to starting position, a feed screw, a feed nut engaging said screw to provide for forward travel of said carriage and locking said carriage against backward movement. 95

6. In a dictation machine, in combination, a record support, a movably mounted record ejector, a carriage movable from a starting position relatively to said record support, a stylus on said carriage adapted to track the record, means positioned to be engaged by said ejector for locking said record ejector against operative movement, means coacting with said locking means to release said ejector when said carriage is moved to starting position, a feed screw, a feed nut engaging said screw to provide for forward travel of said carriage and locking said carriage against backward movement, and means for disengaging said nut from said screw to permit free return of said carriage to its starting position. 100

7. In a dictation machine, in combination, a record support, a movably mounted record ejector, a carriage movable from a starting position relatively to said record support, a stylus mounted on said carriage and movable into and out of operative relation to said record support, means positioned to be engaged by said ejector for locking said record ejector against operative movement, means coacting with said locking means to release said ejector when said carriage is moved to starting position, a feed screw, a feed nut engaging said screw to provide for forward travel of said carriage and locking said carriage against backward movement, and means for moving said stylus out of operative relation to said record support and simultaneously disengaging said feed nut from said screw. 110

8. In a dictation machine, in combination, a record-support, a carriage mounted for movement longitudinally of said support from a starting position, a stylus carrier pivotally mounted upon said carriage and movable to an inoperative position with the stylus out of engagement with a record carried by said support, a feed-screw, a feed-nut pivotally mounted on said carriage, control means for moving said stylus carrier to said inoperative position and simultaneously disengaging said feed-nut to permit the return of said carriage to its starting positon, a record-ejector movable relatively to said record-support for en- 120

- gagement with said record, locking means for said record-ejector to prevent its engagement with the record, and means for releasing said locking means from locking position by said carriage when said carriage is returned to its starting position.
9. In a dictation machine, in combination, a rotatably supported record cylinder, a carriage longitudinally movable relative to said cylinder from its starting position, and provided with a stylus normally positioned to operate on the surface of said cylinder, said stylus being selectively movable into an inoperative position, an ejector longitudinally movable to displace the cylinder from its support, means positioned to be engaged by said ejector and normally effective to prevent the displacement of said cylinder by said ejector, means for rendering said last means ineffective when said carriage is moved to its starting position, releasable carriage feeding means adapted to lock said carriage against free movement when said stylus is in its operative position, and means for moving said stylus to its inoperative position and releasing said carriage feeding and locking means.
10. The combination in a dictation machine comprising a record-support, a movable sound-box carriage having a record-engaging stylus movably mounted thereon, said carriage being movable along said record-support from a starting position, and a record-ejector; of locking means for said record-ejector to prevent its engagement with the record, and means for rendering said locking means ineffective when said carriage is returned to its starting position.
11. The combination in a dictation machine comprising a record support, a movable sound box carriage having a record-engaging stylus movably mounted thereon, said carriage being movable along said record-support from a starting position, and a record-ejector; of locking means for said record-ejector to prevent its engagement with the record, and means for rendering said locking means ineffective when said carriage is returned to its starting position.
12. In a dictation machine, in combination, a frame, a record-support mounted on the frame, a record-ejector movably mounted for freeing a record from said support, a carriage movable on said frame along said record-support from an initial position, a stylus on said carriage adapted to track the record, a latch comprising a pivotally mounted lever and means normally tending to swing said lever about its pivot to hold said latch in position to obstruct the path of movement of said ejector, and means for forcing said latch from said path when the carriage is moved to its initial position.
13. The combination in a dictating machine comprising a record-support, a sound-box carriage movable along said record-support from a starting position and having a record-engaging stylus mounted thereon, and a record-ejector for initiating movement of a record relatively to said record-support for the purpose of ejecting said record from said support; of means adapted normally to interfere with the operation of said record-ejector whereby the said initial movement of said record is prevented, and means associated with said carriage for actuating said interfering means to release said record-ejector upon the return of said carriage to its starting position.
